UNITED STATES PATENT OFFICE.

ARTHUR PENTECOST, OF EAST ORANGE, NEW JERSEY, ASSIGNOR TO WALES ADDING MACHINE COMPANY, OF WILKES-BARRE, PENNSYLVANIA, A CORPORATION OF PENNSYLVANIA.

CALCULATING-MACHINE.

1,328,847.

Specification of Letters Patent.

Patented Jan. 27, 1920.

Application filed November 7, 1916. Serial No. 129,927.

To all whom it may concern:

Be it known that I, ARTHUR PENTECOST, a subject of the King of England, residing at East Orange, Essex county, New Jersey, have invented new and useful Improvements in Calculating-Machines, of which the following is a specification.

More particularly, this invention relates to automatic clear sign printing mechanisms 10 for calculating machines of that style wherein the sign printing hammer is normally in fired or discharged position, this invention being an improvement on the mechanism shown, for example, in U. S. patents to Wales, #940,758, Nov. 23, 1909, and to Schuman, Reissue 13,334, December 5, 1911.

In clear sign printing mechanisms of the above style, it is desirable that the sign printing hammer be automatically set or 20 cocked, incidentally to the performance of some other necessary operation of the machine taking place prior to the introduction of the first item of a new list in the machine, and preferably, subsequently to the 25 clearing of the machine.

One of the objects of this invention is the provision of simple and novel means, controlled by the clearing key, and operable incidentally to the clearing operation, to effect 30 the retraction of the sign printing hammer directly by the usual hammer-resetting member without imposing any strain upon the regular printing hammers.

Heretofore, it has been customary to provide a connection between the units hammer and the sign printing hammer, to restrain the latter against discharging during idle strokes after a clearing operation has taken place. Obviously, this places the clear sign 40 printing directly under the control of the regular printing mechanism, so that in case the regular printing mechanism does not operate, the clear sign mechanism cannot operate.

In this invention, the clear sign printing mechanism is in the nature of an attachment located in, but operable by means independent of the regular printer, and one of the main objects is the provision of means 50 independent of the regular printing mechanism to restrain the sign printing hammer against firing on an idle stroke after a clearing operation.

Another object of this invention is to insure 55 the printing of the clear sign with the

printing of the first item entered in the machine after a clearing operation, by means which is operable independently of the regular printing mechanism, and this I attain by arranging to control the independent 60 clear sign hammer-restraining means from the accumulating mechanism, so that upon the entry of the first amount in the accumulator, the restraining means is tripped to release the hammer, and this object may be 65 accomplished, whether or not the first amount is non-printed.

In some prior devices, the clear sign printing hammer is normally cocked, and necessitates the provision of means to prevent the 70 printing of the clear signal with amounts entered after the first amount, or on idle strokes intervening between the printing of the first amount and the next clearing operation.

By the employment of a normally discharged sign printing hammer which can only be cocked as an incident to a clearing operation, the necessity for such lock as above referred to, is obviated.

To these and other ends, the invention includes certain novel features and combinations of parts, more fully set forth herein-after and particularly pointed out in the claims.

In the accompanying drawings, Figure 1 is a sectional side view, parts being omitted or broken away, illustrating one embodiment of my invention applied to the well known Wales calculating machine;

Fig. 2 is a detail side view, showing the normal, discharged positions of the parts;

Fig. 3 is a detail plan view;

Fig. 4 is a detail side view, parts being broken away to show the coupling mechanism which effects the retraction of the sign printing hammer;

Fig. 5 is a detail, showing the sign printing hammer in cocked position;

Fig. 6 is a fragmentary detail rear view 100 of the printer section, showing the means to reset the sign printing hammer, and the independence of the latter relatively to the regular printing hammers;

Fig. 7 is a fragmentary detail of a means 105 to prevent the printing of the clear sign, when the first item entered in the machine, after a clearing operation, is non-printed;

Fig. 8 is a view in side elevation, showing only the mechanism which operates to re- 110

tain the coupling device between the sign printing hammer and the resetting mechanism, in effective position, and

Fig. 9 is a sectional view through the 5 printer.

Although I have chosen to illustrate my invention as applied to a Wales calculating machine, it will be understood that the invention is applicable to other machines, as 10 well.

Referring to Fig. 1, a base 965 supports side frames 967, between which are located from front to rear, the keyboard or indexing mechanism, the accumulating mechanism, and the printer mechanism, respectively.

Depressing any of the numeral keys 117 arranged in denominational rows on the keyboard, projects stops 115 into the paths of 20 corresponding denominational racks or drive members 310, each of which is pivotally supported on front and rear arms 312 and 311, journaled on the cross shaft 300 and the cross rod 301 mounted in the side frames. 25 Each rear arm 311 is provided with a rearward extension 311^a, any of which may operate the clear sign hammer restraining means hereinafter set forth.

A restraining and restoring bar 205 normally contacts the front supporting arms 312 to retain the drive members retired against the tensions of their drive springs 383 connected to the rear arms 311 and to the restraining and restoring bar 205.

35 Turning the main drive shaft 200 forwardly, swings an arm 210, the outer end of which traverses a cam slot 220^a in a crank 220 connected to the restraining and restoring bar 205, to withdraw the latter from in 40 front of the arms 312, and permit the drive springs 383 to advance the racks 310 until the latter are arrested by the projected stops 115, or by rack detents 221 in those denominations wherein no keys have been depressed.

The main drive shaft 200 on its forward stroke, also advances a trip rod 303 supported by depending radius bars 323 journaled on the cross shaft 300, and connected 50 by links 214 with arms 212, 210 on the main drive shaft. Near the end of the forward stroke of the main drive shaft, after the racks 310 have completed their advance, the trip rod 303 displaces the well known Wales 55 counter-supporting mechanism (not shown) to mesh the pinions 435 of a series of denominational counters 490 with their respective racks 310. The counter-supporting means above referred to, is shown in U. S. 60 patent to Wales, 940,758, heretofore mentioned, and is also found in U. S. patents to Wales 797,032, April 15, 1905; McFarland, 842,232, January 29, 1907, and White, 940,766, Nov. 23, 1909.

The main drive shaft on its return stroke, 65 forces the restraining and restoring bar 205 against the arms 312 of the advanced racks to return the latter to normal position, and the racks during their retirement, turn the pinions 435, and associated counters, to register thereon the amount represented by the depressed keys.

The trip rod 303 is also retired during such return stroke, near the end of which, it operates the counter-supporting mechanism to disengage the counters from their drive members, after the latter have been retired, and thus forms means to control the engagement and disengagement of the counters and their drive members.

The rack detents 221 also arrest the racks or counter drive members 310 against advance on idle strokes of the main drive shaft when no keys are depressed.

Suitable carrying mechanism, not shown, 85 transfers the "tens" from counters of lower denomination to those of next higher denomination.

The rack-supporting arms 312, 311 rock as the racks advance and retire, and links 90 515 connect the rearward extensions 311^a of the rear arms 311 with denominational typecarriers 514 bearing types 561, to position the types corresponding to the depressed keys, at the printing line of a platen 2094, 95 as the racks advance against the key-set stops 115, and to return the typecarriers to normal position upon the retirement of the racks.

I utilize a printing mechanism substantially like that shown in U. S. patents to McFarland, 924,264, June 8, 1909, Wales, 940,758, above mentioned, or Hunter & Küntzler, 1,054,554, February 25, 1913, to which reference is made for a more complete disclosure thereof.

Individual hammer pawls 511 (Fig. 9) journaled on a cross rod 504 mounted in the printer side frames 565, hold the denominational printing hammers 510, journaled on 110 shaft 500, in normally retracted or cocked positions against the tension of the hammer drive springs 580.

The hammers 510 are also under the control of a universal catch 518 which is displaced only after the types are positioned at the printing line, to permit the hammers to strike firing pins 562 and drive the latter against the types to effect the imprint of the amount set up on the keyboard.

As the extension arms 311^a rock upwardly during the forward stroke of the main drive shaft, they permit trip bars 513, under the influence of springs 583, to rise and contact the tails of the individual hammer pawls 511 125 to release the pawls from the corresponding hammers. Suitable cross-over tails on the respective hammer pawls 511 of the regular

printing section, trip the pawls to the right of a positively tripped pawl to effect cipher printing to the right in the usual manner.

The hammers do not fire upon the release 5 of the pawls, because restrained by the universal catch 518.

The trip rod 303, during its advance stroke, draws with it a link 526 (Fig. 1) connected to a lever 524 journaled on the 10 cross shaft 508, to rock the lever, such motion being transmitted from the lever 524 through a link 527 to another lever 525 fast on a rock shaft 500 journaled in the printer side frames 565. Arms 519 (Figs. 1 and 15 9) fixed to the shaft 500, support the hammer-resetting bail or member 509 which normally lies against the printing hammers 510, but is withdrawn therefrom by the foregoing linkage, on the forward stroke of the 20 main drive shaft. A link 525^a (Fig. 1) connects lever 525 with a crank 513^a fast on a tensioning shaft 502 journaled in the printer side frames 565, to turn the shaft and with it, a pair of arms 512^a (Fig. 9) 25 supporting a bail 505 to which the upper ends of the hammer driving springs 580 are secured, the opposite ends of these springs being connected to the respective printing hammers 510. The hammer drive springs 30 580 are thus tensioned on the forward stroke of the main drive shaft, to swing the hammers 510 when the latter are released, against the firing pins 562 to print the types positioned at the printing line.

35 A link 528 (Fig. 1) connected to the rocking lever 525, has a slotted connection with a crank 517 on a shaft 502 journaled in the printer side frames, the universal catch 518 being fast on this shaft, so that as the main 40 drive shaft 200 approaches the end of its forward stroke, the universal catch is lifted against the tension of a spring 584 (Fig. 4) to release the hammers for operation.

The various printer mechanism, above set 45 forth, retire to their normal idle positions on the return stroke of the main drive shaft. The hammer-resetting member 519 recocks or retracts the discharged hammers, the tension of the springs 580 is relaxed, and spring 50 584 snaps the universal catch over the re-stored hammers. The extensions 311^a return the typecarriers 514 and withdraw the trip bars 513 to enable the individual hammer pawls 511 to lock the respective printing 55 hammers in cocked position.

Depressing a total or clearing key 327, (Fig. 8) and operating the main drive shaft, effects the restoration of the counters 490 to zero to clear the machine preparatory to 60 commencing another accumulation, in the well known manner set forth, for example, in U. S. patent to McFarland, No. 842,232, January 29, 1907.

Depression of a non-print key 523 (Fig. 65 1) against the tension of its restoring spring

589, rocks a non-print bail or comb 524^a, journaled on the cross pin 506 to interpose the teeth of the comb in the paths of the trip bars 513 to arrest the latter and thereby prevent them from displacing the individual hammer pawls 511^a. Thus, the hammers remain cocked even when the universal catch 518 is released, as set forth more in detail in U. S. patents to Wales, No. 902,125, October 27, 1908, and to McFarland, No. 75 924,264, June 8, 1909.

For a more complete understanding of the Wales mechanism, attention is directed to U. S. patents to McFarland & Wales, No. 880,157, February 25, 1908; Bickford, No. 80 1,066,700, July 8, 1913; and Wilgus, No. 1,133,596, March 30, 1915, in addition to those heretofore cited.

The foregoing mechanism constitutes no part of the present invention, except in so far as it may be combined with the novel features now to be set forth.

The clear sign printing mechanism herein illustrated, is auxiliary to and operates independently of the regular printing hammers. 90 The sign printing hammer 1, (Fig. 2) is journaled on the cross shaft 500, similarly to and preferably to the right of the regular printing hammers 510, and is driven by a spring 580^a, one end of which is connected 95 by a shackle 512 to the hammer, the opposite end of the spring being connected to the tensioning bail 505. The sign printing hammer 1 unlike the regular printing hammers, normally lies in discharged or fired 100 position (Fig. 2) adjacent a firing pin or plunger 562, which lies in line with the heel of the usual Wales clear signal typecarrier 513^b journaled on a stud 559 projecting laterally from the right hand side frame 565 105 of the printer. The usual Wales clear sign type $\odot$ is mounted on the toe 513^c of the typecarrier, opposite the printing line. A spring 581 attached to a tail 513^d of the type carrier, normally maintains the latter in retracted position against the adjacent end of the firing pin 562, or of a flange 565^a of the side frame.

I have contrived a simple and improved clearing key-controlled coupler mechanism 115 located within the machine, where it cannot be injured, to utilize the usual hammer-resetting member 519,509 to cock or retract the sign printing hammer 1.

Thus, the stem of the clear key 327 (Figs. 120 1 and 8) carries a stud 352, which, upon the depression of the key, wipes along a cam 326^a on a longitudinally-extending, adjusting bar 326 to shift the bar rearwardly 125 against the tension of its restoring spring 682. A pin and slot connection 360 guides the forward end of the adjusting bar, the rear end of which is connected to a crank 1814 on a utility cross shaft 1801 journaled in the side frames 967. The adjusting bar 130

when shifted, turns the shaft 1801, and with it a crank 2 (Fig. 2) on the opposite end of the shaft, which operates a vertically shiftable support or carrier 3, the upper end of which is slotted, as at 4, to embrace the cross rod 504^a for guidance. Pins 5 on the offset head 6 of the carrier 3 enter slots 7 in a horizontally shiftable coupling bar or member 8, the pins limiting and guiding the throw of the coupling member. The rear end of the coupling member 8 projects beyond the head 6, and has an open or L-shaped slot 9 formed therein to embrace a stud or actuator 10, on the adjacent arm 519 of the usual hammer-resetting member. A spring 11 connecting the head 6 and the coupling member 8, normally retains the latter at one limit of its throw, in which position, the actuator or stud 10 is located at the confluence of the long and short arms of the slot 9 in the coupling member, as shown in Fig. 2.

Ordinarily, on stroking the main drive shaft 200, the actuator 10 idly traverses the long arm of the slot 9, but upon the depression of the clearing key 327, the throw imparted to the adjusting bar 326 is sufficient to lift the adjustable carrier 3 and its coupling member 8 relatively to the actuator 10, to cause the short arm of the slot 9 to embrace the actuator (see Fig. 4), the walls of which shorter slot lie at substantially right angles to the path traversed by the actuator.

The support 3 and coupling member 8 are sustained in this position by the usual clearing key latch 216 (Fig. 1) which engages a stud 336 on the usual set lever 317 connected to the clearing key 327 by the catch 326^b, the latch 216 and the usual locking rib 217 on the segment 211, operating to maintain the clearing key in depressed position during the forward stroke of the main drive shaft, as is customary in the Wales machine.

It will be remembered that the main drive shaft 200 on its forward stroke, advances the trip rod 303 which through the linkage 526, 524, 527 and 525, rocks the shaft 500 to withdraw the hammer resetting the bail 509 mounted in arms 519 fast on the shaft 500; out of the paths of the hammers 510, and that one of the arms 519 which is thus rocked, carries the clear sign actuator or stud 10, the coupling member 8 adjusted so that the short arm of the slot 9 embraces the actuator 10, the latter and the hammer-resetting member 519, on their withdrawal from the path of the usual printing hammers 510 during the forward stroke of the main drive shaft, will draw the coupling member 8 rearwardly.

The coupling member 8 carries a hooked draft member 12 (Figs. 2, 4 and 5) pivoted thereto at 13. A follower 14 on the draft member normally rests upon a dwell 15 formed on the head 6 of the carrier, and a

spring 16 connects the free end of the draft member to the coupler and holds the follower in contact with the dwell.

The hooked free end of the draft member 12 normally lies in front of an angular projection or keeper 17 best shown in Fig. 4 on the discharged sign printing hammer 1; (Fig. 2) and when the carrier 3 is lifted by depressing the clearing key, the free end of the draft member is lifted to a plane 70 above the keeper 17. As the coupler 8 and draft member 12 are drawn rearwardly by the actuator 10, the follower 14 on the draft member rides off of the dwell and down the adjacent cam face 18 on the head 6 of the carrier, under the influence of the spring 16, which brings the draft member in line with the projection 17 on the sign printing hammer, and as the coupler continues its rearward travel, the outer end of the draft member 12, which is inclined to correspond with the adjacent beveled face of the projection 17, rides up and over the projection until the hook or draft member can snap over the keeper, as shown in Fig. 4. This engagement of the draft member and keeper takes place near the end of the forward stroke of the main drive shaft.

On the return stroke of the main drive shaft, the actuator 10 on the resetting member 519, by its contact with the front wall of the shorter arm of the slot 9, advances the coupling toward its normal position, and the draft member carried by the coupling retracts the sign printing hammer 1 against 95 the tension of its firing spring 580^a. The sign printing hammer is recessed at 19, (Fig. 5) at a point opposite the hammer-resetting bail 509, to prevent the resetting bail from cocking the sign printing hammer at 105 every operation of the main drive shaft.

The return of the coupling member 8 and the draft member 12 to normal position, brings the follower 14 on the draft member against the cam face 18 on the carrier, up 110 which the follower rides to release the draft member from the keeper 17 on the sign printing hammer and tension the spring 16.

A latch of detainer 20 (Fig. 2) locks the sign printing hammer 1 in cocked or retracted position, (see Fig. 5) prior to the release of the draft member, said latch being pivoted on the cross rod 504 independently of the individual hammer pawls 511. A spring 21 connects the latch with a link 22 115 journaled at its upper end on the cross rod 504, and a stop 23 on the link lies in the path of a shoulder 24 on the latch to limit the throw of the latter under the influence of the spring. As the sign printing hammer 1 reaches its set position, near the end of the return stroke of the main drive shaft, a lip 25 thereon rides under the latch 20 which snaps over the lip to hold the hammer cocked, as in Fig. 5. An abutment 507 120

(Fig. 2) limits the swing of the link 22 in one direction, to hold the latch in position to snap over the lip on the sign printing hammer. When the hammer is in its set position, it lies behind the universal catch 518.

Obviously, by swinging the link 22 forwardly, the stop 23 will press against the shoulder 24 of the latch 20 to lift the latter and release the sign printing hammer to the action of its drive spring 580^a. An extensible trip bar 27, 29, one end of which is pivotally connected at 28 to the link, and the other end of which carries a slotted extension 29 embracing the trip rod 303, shifts the link to displace the latch 20. Pins 30 on the extension enter elongated apertures 31 in the forward end of the trip bar 27 to enable the extension to shift relatively to the trip bar; and a spring 32 connects the extension and trip bar to normally maintain the extension at the inner limit of its travel.

The slot 33 in the extension 29 is open at one end to facilitate assembly and disassembly relatively to the trip bar.

The trip bar 303 on its advance, at every operation of the machine, idly traverses the slot 33 until it reaches the outer end wall thereof, whereupon, it draws the extension 29 forwardly and tensions the spring 32 sufficiently to rock the link 22 and force the stop 23 against the latch 20 to cause the latter to release the sign printing hammer for operation, providing the sign printing hammer is in cocked position.

So far as explained, the clear sign would be printed on the first stroke after a clearing operation, but I provide novel means operable independently of the regular printing mechanism, to prevent the operation of the sign printing hammer after it has been set, until the first amount is entered in the machine, and then to enable the clear sign to be printed with such first amount and as an incident to its introduction into the machine.

Such means, in the present embodiment, comprises a universal bar 34 (Figs. 1-4) carried by arms 35 journaled on the cross rod 301, the bar conveniently extending across the extensions 311^a of the rear rack supporting arms 311. An arresting arm or lock 36 projects rearwardly from the universal bar 34 or one of its arms 35, to a point in front of an abutment 37 on the trip link 22, the rear end of the arresting arm terminating in an abrupt face 38 confronting the abutment.

Upon any idle stroke or operation of the machine, that is, one wherein no keys have been depressed, the trip rod 303 on its advance, will tension the spring 32, but the link 22 cannot yield to such tension because of the opposition of the arresting arm 36, in its path.

Upon the introduction of an amount into

the machine, and the advance of the main drive shaft on its forward stroke, the racks or drive members 310 advance, preparatory to turning the counters, and rock the extensions 311^a (see Fig. 4) upwardly, and the extensions, or any of them lift the universal bar 34 to displace the arresting arm 36 relatively to the abutment 37, to thereby free the trip link 22 for operation when the spring 32 is tensioned by the trip bar 303 near the end of its forward stroke. The trip link, on such forward throw, will press the stop 23 against the shoulder of the latch 20 to displace the latter, and if the sign printing hammer is cocked, to release the hammer for operation.

Preferably, the sign printing hammer is released prior to the release of the universal catch 518, so that the latter will detain the sign printing hammer until all the printing hammers are released, but this is not a necessary feature of the invention, as the sign printing hammer may be arranged so as not to contact the universal catch, or may be released after the catch has been lifted.

If the trip link 22 should remain in its forward or tripped position, due to gravity, for instance, the stop 23 might tend to prevent the latch 20 from becoming effective when the sign printing hammer is again cocked. To insure the return of the trip link 22 to, and its retention in, normal position, (Fig. 2,) the lower rear edge of the arresting arm 36 is beveled, as at 39, so as to ride over the abutment 37 on the return of the universal bar 34 with the extension 311^a to normal position, to force the link 22 rearwardly until the abrupt face 38 contacts the abutment. The extent of the face 38 is such that it will release the abutment upon the elevation of the rear extensions 311^a when registering "one" in the accumulator, but not when the extensions lift slightly on idle strokes, at which times the detents 221 arrest the advance of the racks.

In that style of machine typified by the well known Wales construction, the clearing key 327 is released from a depressed position at the end of the forward stroke and returns to normal position, as shown in Fig. 8.

Such release and return of the clearing key might permit the return of the coupler member 8 and the carrier 3, from their effective elevated positions to normal idle positions, prior to the resetting of the clear sign printing hammer 1, were it not that means is provided to retain the coupler where adjusted during the return stroke of the main shaft.

Such retaining means (Figs. 1 & 8) includes draft links 615 pivotally connected to the corresponding arms of a pair of rocker levers 615^a, and having closed slots 615^b embracing the trip rod 303. The

rocker levers 615^a are fixed to the cross shaft 508, on which is fastened a pair of lifting cranks 626, having studs 654 adapted to contact shoulders 1812^a on the depending stems 5 1812 pivoted to supporting sockets 1856 for the ribbon mechanism, not shown. The sockets 1856 are loosely seated in the frame parts of the machine.

Normally, the trip rod 303 lies at the rear 10 ends of the slots 615^b in the draft links as shown in Fig. 1, and during its forward sweep, the trip rod travels idly in the slots until near the end of the stroke, whereupon, it contacts the front end walls of the slots 15 to draw the draft links 615 forwardly and thereby rock the shaft 508 to raise the lifting cranks 626, as shown in Fig. 8.

The shoulders 1812^a normally lie beyond the paths of travel of the cranks, but the 20 depression of the clearing key 327, turns the utility cross shaft 1801 forwardly, as above explained, and with it a pair of guide arms 1813 having slotted heads 1813^a through which the stems 1812 pass.

25 Light springs 281 connect the guide arms 1813 and stems 1812, which springs are tensioned when the arms 1813 rock forwardly upon the depression of the clearing key, to shift the stems 1812 and position the shoulders 1812^a above the studs 654 of the lifting cranks 626.

With the parts in adjusted position, the cross shaft 508, when rotated by the trip rod 303 on its forward stroke, causes the 35 cranks 626 to lift the stems 1812 and sockets 1856 to position a different field of the ribbon opposite the printing line, against the tension of comparatively strong restoring springs 1881 encircling the sockets 1856.

40 The sockets are maintained in this position, during the return stroke, by spring-impelled catches 616 pivoted on a cross rod 607 and adapted to snap over ears 615^c on arms 615^d of the rocking levers 615^a when 45 the latter have been actuated by the draft links 615 and trip rod 303 on their forward stroke.

The entrance of the catches 616 into the paths of the ears 615^c on the rocker levers 50 is insured by swinging the rocker levers below the catches, as shown in Fig. 8, which illustrates the positions of the parts at the end of the forward stroke.

As the main drive shaft 200 returns, the 55 trip rod 303 releases its pressure against the forward ends of the slotted draft links 615, which thereupon retract under the influence of the springs 384 to enable the levers 615^a to rise until arrested by the 60 catches 616. Obviously, this slightly lowers the cranks 626 and the sockets 1856, but not sufficiently to permit the disconnection of the stems 1812 from the studs 654 on the cranks, on account of the pressure of the 65 shoulders 1812^a against the studs 654 caused

by the strong springs 1881, which pressure cannot be overcome by the weaker springs 281 and 682.

The forward edges of the catches 616, when in engagement with the rocking levers 70 615^a, have entered the path of the trip rod 303, and maintain the lifting cranks 626 in adjusted position, until the trip rod 303, near the end of its return stroke, strikes the catches and retires them to enable the rocking levers 615^a and the lifting cranks 626 to 75 return to normal positions, under the influence of their springs 384.

The clearing key 327 restores to normal position at the end of the forward stroke 80 of the main drive shaft, thereby releasing the adjusting bar 326 and the utility shaft 1801 controlling the position of the coupler 8, to the action of the restoring spring 682, but owing to the firm contact of the shoulders 1812^a with the lifting studs 654 on the cranks 626, caused by the strong springs 1881, the weaker springs 682 and 281 for restoring the utility shaft and guide arms 1813, are unable to disengage the stems 1812 90 from the lifting cranks, and the arms 1813 are prevented by such stems, from returning to normal position until the catches 616 are released, and thus lock the utility shaft 1801, which supports the carrier 3 and coupler 8, 95 where adjusted, until the sign printing hammer has been cocked.

The latches 616, when released, enable the springs 682 and 281, aided by the weight of the parts, to restore the adjusting bar 326 100 and lower the carrier 3 so that the long arm of slot 9 is registered with the actuator 10 which, on succeeding strokes, idly traverses the slot.

A special key 327^a, (Fig. 1) similar to the 105 clearing key 327, is provided for effecting the well known sub-totaling operation, and to prevent the cocking of the normally discharged sign printing hammer 1 during such operation, I provide the sub-total key with a 110 wiper 352^a, adapted to ride along a cam face 326^c formed on the adjusting bar 326, which cam face is more abrupt than the cam face 326^a engaged by the wiper on the clearing key 327.

115 Depression of the sub-total key 327^a will, therefore, impart a longer stroke to the adjusting bar and through the utility shaft 1801 and crank 2, will lift the carrier 3 to a position above that occupied when the clearing key is depressed.

The short arm of the slot 9 in the coupler 8 is preferably open at one end to accommodate this increased throw of the carrier and its coupler, so that the coupler disengages 125 itself from the actuator 10 on the usual hammer-resetting member 519, to permit the actuator to rock idly back and forth beneath the coupler during the forward and return strokes of the main drive shaft.

The printing of the clear sign near the end of the forward stroke of the main drive shaft takes place preliminary to the registration of an amount in the accumulator, 5 which occurs on the return stroke, and as an incident thereto.

It may be desired to prevent the printing of the clear sign when the first item is non-printed, to accomplish which, I provide a 10 shifting arm 524^b (Figs. 1, 2, 4 and 7) projecting rearwardly from the usual Wales non-print bail 524^a. Depression of the non-print key 523 rocks the non-print bail 524^a and raises the shifting arm 524^b to contact 15 the lower end of a locking slide 40 having pin and slot connections 41, with a stationary part of the printer frame. The shifting arm 524^b forces the locking slide upwardly until its upper end contacts with, or 20 lies immediately below, the tail 513^a of the clear sign typecarrier 513^b, when the latter is in normal position.

The sign printing hammer 1, upon its release, drives the firing pin 562 against the 25 heel of the clear sign typecarrier 513^b, but the locking slide 40 in the path of the tail 513^a prevents the typecarrier from striking against the platen so that no clear signal is printed, when the non-print key is depressed.

Furthermore, the clear sign printing hammer 1 upon its release, remains in discharged 30 position so that no clear sign can be obtained with any subsequent printed amount in the same list of items.

Changes may be made in the form and arrangement of the several parts without departing from the spirit and scope of this invention.

What I claim is:—

40 1. In a calculating machine, the combination with accumulating, and regular printing mechanisms, including printing hammers; of an auxiliary sign printing device, including a sign printing hammer; means to cock the sign printing hammer; a latch to retain the sign printing hammer in cocked position; means to trip the latch; and locking means operable independently of the regular printing hammers and displaceable 45 preliminary to the registration of the first amount on the accumulating mechanism, to prevent the release of the latch during idle strokes intervening between the clearing of the accumulating mechanism, and the introduction of the first amount into the machine.

55 2. In a calculating machine, the combination with a keyboard; and accumulating, and regular printing mechanisms, including printing hammers, hammer latches, means to trip the latches, and means to reset the 60 hammers; of an auxiliary sign printing device, including a sign printing hammer; means to releasably connect the sign printing hammer directly with the regular hammer-resetting means, to cock the sign print-

ing hammer; a latch to retain the sign printing hammer in cocked position; means separate from the latch tripping means of the regular printing mechanism to trip the sign printing hammer latch; a lock shiftable relatively to the latch tripping means for the sign printing hammer, to prevent an effective operation of the latch tripping means; and means operable as an incident to the registration of the first amount on the accumulating mechanism, and separate from the regular latch tripping means, to displace the lock. 70

3. In a calculating machine, the combination with accumulating, clearing, and regular printing mechanisms, the last including printing hammers; and a hammer-resetting member; of a sign printing mechanism, including a sign printing hammer; means operable coincidentally with the clearing of 80 the accumulator by the clearing mechanism, to enable the hammer-resetting member to cock the sign printing hammer; means to detain the sign printing hammer in cocked position; means actuated at every operation 85 of the main drive shaft, to trip the detaining means; a lock to prevent the release of the detaining means; and means operable prior to the actual registration of an amount on the accumulator, to displace the lock. 90

4. In a calculating machine, the combination with accumulating, clearing, and regular printing mechanisms, the last including printing hammers, and means to reset the same; of an auxiliary sign printing device, 100 including a sign printing hammer; means operable incidentally with the zeroizing of the accumulators by the clearing mechanism, to enable the hammer-resetting mechanism to cock the sign printing hammer; a latch 105 independent of the regular printing hammers, to retain the sign printing hammer in cocked position; means actuated at every operation of the machine, to trip the latch; and locking means releasable independently 110 of the printing hammers and disabled preliminary to the registration of an amount in the accumulator, to prevent the release of the latch.

5. In a calculating machine, the combination with accumulating, clearing, and regular printing mechanisms, the last including printing hammers; and a hammer-resetting member; of a sign printing mechanism, including a sign printing hammer; means operable coincidentally with the clearing of 115 the accumulator by the clearing mechanism, to enable the hammer-resetting member to cock the sign printing hammer; means to disable the last named means upon the retraction of the sign printing hammer; means to detain the sign printing hammer in cocked position; means actuated at every operation 120 of the main drive shaft, to trip the detaining means; a lock to prevent the release of 125 the sign printing hammer. 130

the detaining means; and means operable prior to the actual registration of an amount on the accumulator, to displace the lock.

6. In a calculating machine, the combination with accumulating, clearing, and regular printing mechanisms, the last including printing hammers; of an auxiliary, sign printing mechanism, including a sign printing hammer; means to cock the sign printing hammer; detaining means to hold the sign printing hammer in cocked position; flexible means to trip the hammer-detaining means; and means operable independently of the printing hammers and

shiftable to idle position preliminary to the actual registration of an amount on the accumulator, to normally prevent the release of the hammer-detaining means, during idle strokes intervening between the cocking of the sign printing hammer, and the introduction of an amount into the machine.

7. In a calculating machine, the combination with accumulating, clearing, and regular printing mechanisms, the last including printing hammers; of an auxiliary, sign printing mechanism, including a sign printing hammer; means to cock the sign printing hammer; detaining means to hold the sign printing hammer in cocked position; means to trip the hammer-detaining means; and means operable independently of the printing hammers and displaced preliminary to the actual registration of the first amount on the accumulator, to normally prevent the release of the hammer-detaining means, during the idle strokes intervening between the cocking of the hammer, and the introduction of an amount into the machine.

8. In a calculating machine, the combination with a main drive shaft; and accumulating, clearing, and regular printing mechanisms, the last including printing hammers, and resetting means therefor; of an auxiliary, sign printing mechanism, including a sign printing hammer; means to enable the regular hammer resetting means to directly cock the sign printing hammer; detaining means to hold the sign printing hammer in cocked position; a trip link connected to and adapted to disable the detaining means; a resilient member actuated at each operation of the main drive shaft, to operate the trip link, and release the detaining means; a displaceable lock to prevent effective actuation of the trip link and cause an extension of the resilient means; and means to displace the lock.

9. In a calculating machine, the combination with a main drive shaft; and accumulating, clearing, and regular printing mechanisms, the last including printing hammers, and resetting means therefor; of an auxiliary, sign printing mechanism, including a sign printing hammer; means to enable the regular hammer resetting means to directly

cock the sign printing hammer; detaining means to hold the sign printing hammer in cocked position; a trip link adapted to disable the detaining means; a trip rod actuated at each operation of the main drive shaft; and a flexible bar to connect the link and trip rod, to cause the link to trip the detaining means and free the sign printing hammer.

10. In a calculating machine, the combination with accumulating, clearing, and regular printing mechanisms, the last including printing hammers; of an auxiliary, sign printing mechanism, including a sign printing hammer; means to cock the sign printing hammer; detaining means to hold the sign printing hammer in cocked position; a trip link to disable the detaining means; a shiftable trip rod; a bar connected to the link and having an extension loosely connected to the trip rod; and a spring to connect the bar and extension.

11. In a calculating machine, the combination with accumulating, clearing, and regular printing mechanisms, the last including printing hammers; of an auxiliary, sign printing mechanism, including a sign printing hammer; means to cock the sign printing hammer; detaining means to hold the sign printing hammer in cocked position; a trip member to disable the detaining means; an extensible bar connected to the trip member; means to normally retract the extensible bar; and a shiftable trip rod adapted to extend the bar to tension the retracting means to operate the trip member.

12. In a calculating machine, the combination with accumulating, clearing, and regular printing mechanisms, the last including printing hammers; of an auxiliary, sign printing mechanism, including a sign printing hammer; means to cock the sign printing hammer; detaining means to hold the sign printing hammer in cocked position; a trip member to disable the detaining means; a bar connected to the trip member and having an extension, slidably mounted thereon; a spring to hold the extension retracted; and a shiftable trip rod to advance the extension and tension the spring to operate the trip member.

13. In a calculating machine, the combination with accumulating, clearing, and regular printing mechanisms, the latter including printing hammers, and latches to retain the regular printing hammers in set position; of an auxiliary, sign printing device, including a sign printing hammer; means controlled by the clearing mechanism, to cock the sign printing hammer; a latch to retain the sign printing hammer in cocked position; means to trip the latch to release the hammer for operation; and locking means for the sign printing hammer latch separate from the regular printing

- mechanism, to resist the latch-tripping means, and itself displaceable as an incident to the operation of the accumulating mechanism.
- 5 14. In a calculating machine, the combination with accumulating, clearing, and regular printing mechanisms, the last including printing hammers; of an auxiliary, sign printing device, including a sign printing hammer; means to cock the sign printing hammer; a latch individual to the sign printing hammer to retain the latter in cocked position; means to trip the latch; and locking means for the latch, operable 10 independently of the regular printing mechanism, and automatically displaceable incidentally, and as a necessary preliminary, to the entry of an item on the accumulator after a clearing operation.
- 10 15. In a calculating machine, the combination with an accumulator, including a series of counters, and drive members therefor; and a printer mechanism, including regular printing hammers, and a hammer-resetting member; of an auxiliary, sign printing mechanism, including a sign printing hammer; adjustable coupling mechanism between the sign printing hammer and the hammer-resetting member to enable the 15 latter to cock the sign printing hammer; a latch to detain the sign printing hammer in cocked position; means to trip the latch, and means directly controlled from the accumulator drive members to normally lock the latch against release until the entry of the first amount into the machine.
- 20 16. In a calculating machine, the combination with an accumulator, including a series of counters, drive members therefor; 25 shiftable supports for the drive members, having extensions; and a printer mechanism, including regular printing hammers, and a hammer-resetting member; of an auxiliary, sign printing mechanism, including 30 a sign printing hammer, adjustable means to couple the resetting member and sign printing hammer, to cock the latter; a latch to detain the sign printing hammer in cocked position; means to trip the latch; a 35 universal bar operable by any of the drive member-supporting extensions; and a lock controlled thereby and normally lying in the path of the latch-tripping means to prevent the release of the latch.
- 40 17. In a calculating machine, the combination with an accumulator; including a series of counters, drive members therefor; means to control the engagement and disengagement of the counters and their drive members; and a regular printer section; of 45 an auxiliary sign printing mechanism, including a sign printing hammer; adjustable means to effect the retraction of the hammer to cocked position; a latch to detain 50 the sign printing hammer in cocked posi- tion; a tripping means for the latch, including a trip link having a stop adapted to rock the latch to idle position; a flexible trip bar to connect the link and the counter-controlling means; and a lock displaced 55 by the entry of an amount into the machine, to normally hold the latch against release.
- 5 18. In a sign printing mechanism for calculating machines, the combination with the regular printing hammers, and the hammer-resetting member; of a sign printing hammer; a coupling mechanism between the sign printing hammer and resetting member, including an adjustable support; a coupler shiftably mounted on the support; means to adjust the coupler and support relatively to the resetting member to connect the coupler and the hammer-resetting member; a draft member carried by the coupler and shifted thereby to engage the sign printing hammer; a follower on the draft member; a cam on which the follower rides to disconnect the draft member and sign printing hammer when the latter is cocked; 10 a latch to retain the sign printing hammer in cocked position; and means to trip the latch upon the entry of an amount into the machine.
- 10 19. In a calculating machine, the combination with accumulating, clearing and regular printing mechanisms, the last including printing hammers, and a hammer-resetting member; of an auxiliary, sign printing device, including a sign printing 15 hammer; means to couple the resetting member and the sign printing hammer, as an incident to a clearing operation, comprising an actuator carried by the hammer-resetting member; a normally inoperative coupler adjustable relatively to the actuator and controlled by the clearing mechanism; a draft member on the coupler to releasably engage the sign printing hammer and shift it to cocked position; means to detain the sign 20 printing hammer in cocked position; means to trip the detaining means; and means to prevent the release of the detaining means until the first item is being entered in the machine.
- 20 20. In a calculating machine, the combination with a printer section having printing hammers, and hammer-resetting means; of an auxiliary, sign printing mechanism, including a sign printing hammer having a lug thereon; an actuator on the hammer-resetting means; an adjustable support; a coupler shiftable relatively to the support and having an angular slot; the actuator adapted 25 to idly traverse one arm of the slot and normally lying in register with the remaining arm of the slot; means to shift the support to cause the last named arm of the slot to embrace the actuator; a draft member pivoted to the coupler, and having a hook adapt- 30

ed to engage the lug on the sign printing hammer, to enable the actuator to shift the sign printing hammer to cocked position; a latch to hold the sign printing hammer in 5 cocked position; a follower on the draft member; a cam wiped by the follower as the sign printing hammer is cocked to release the draft member from said hammer; and means to trip the latch upon the entry of an 10 amount into the machine.

21. In a calculating machine, the combination with a main drive shaft; an accumulator; clearing mechanism therefor; and a regular printing mechanism, including 15 hammers, and a hammer-resetting member; of an auxiliary sign printing mechanism automatically operable independently of the regular printing mechanism, including a sign printing hammer; adjustable means to 20 temporarily couple the sign printing hammer and the regular hammer-resetting member, to cock the sign printing hammer; means to disengage the sign printing hammer from the hammer-resetting member as 25 the hammer reaches its cocked position; means releasable independently of the regular printing mechanism, to detain the hammer in cocked position; means operable on each operation of the main drive shaft to 30 trip the detaining means; and means displaceable only as a necessary preliminary to the entry of the first amount in the accumulators to normally lock the hammer-detaining means against release.

35 22. In a sign printing mechanism for calculating machines, the combination with the regular printing hammers; and the hammer-resetting member; of a sign printing hammer; an adjustable coupling mechanism between the sign printing hammer and the resetting member; including a shiftable coupler; means to adjust the coupling mechanism to connect the coupler and the hammer-resetting member; a draft member carried 40 by the coupler and shiftable therewith to engage the sign printing hammer and retract it to cocked position; means to disable the draft member; means to detain the sign printing hammer in cocked position; and 45 means to trip the detaining means upon the entry of an amount into the machine.

50 23. In a calculating machine, the combination with a main drive shaft; and accumulating, printing and clearing mechanisms; of an auxiliary sign printing mechanism, including a sign printing hammer; means to cock the hammer preliminary to the printing of the first item after a clearing operation; means releasable independently 55 of the regular printing mechanism to detain the sign printing hammer cocked; means tending to trip the hammer-detaining means at each operation of the main drive shaft; and locking means automatically displaceable as a necessary preliminary to the entry 60

of an amount on the accumulator to prevent the tripping of the detaining means, during idle strokes intervening between the cocking of the hammer and the introduction of an item into the machine.

24. In a calculating machine, the combination with accumulating mechanism; of an auxiliary, sign printing mechanism, including a sign printing hammer; means to cock the sign printing hammer; detaining 70 means to hold the sign printing hammer in cocked position; a trip rod shiftable at each operation of the machine; a trip member to disable the detaining means; a spring connection between the trip member and trip 75 rod; and locking means for the trip member displaceable as a preliminary to the registration of an amount on the accumulating mechanism.

25. In a calculating machine, the combination with accumulating, and regular printing mechanisms; of an auxiliary sign printing mechanism, including sign printing hammer; means to cock the sign printing hammer; detaining means individual 85 to the sign printing hammer to hold the latter in cocked position; yielding means tensioned at each operation of the machine to trip the detaining means; and locking means displaceable as a preliminary to the 90 registration of an amount on the accumulating mechanism, to prevent the tripping of the detaining means during idle strokes intervening between the cocking of the hammer and the introduction of an item into the 95 machine.

26. In a calculating machine, the combination with an accumulator; clearing mechanism therefor; a regular printing mechanism, and means to prevent the printing 105 of amounts registered on the accumulator; of an auxiliary sign printing mechanism automatically operable independently of the regular printing mechanism to print a clear sign to indicate the fact that the accumulator was clear when the first amount was 110 registered after a clearing operation; and a lock operable by the non-print means to prevent the effective operation of the sign printing mechanism.

27. In a calculating machine, the combination with an accumulator; clearing mechanism therefor; a regular printing mechanism, including hammers, and a hammer-resetting member; and means to prevent the 120 printing of amounts registered on the accumulator; of an auxiliary, sign printing mechanism automatically operable independently of the regular printing mechanism, including a sign printing hammer; 125 means to cock the sign printing hammer; a latch to detain the sign printing hammer in cocked position; means to trip the latch; a locking means for the latch, operable as an incident to the registration of an amount 130

in the accumulator to release the latch to the action of its trip means; and a locking bar adjusted by the non-print means to prevent the printing of the sign upon the release of the latch.

28. In a calculating machine, the combination with accumulating, and regular printing mechanism, the latter including printing hammers; and a non-print mechanism; of an auxiliary sign printing device, including a sign printing hammer; means to cock the sign printing hammer; a latch to retain the sign printing hammer in cocked position; means to trip the latch; a shiftable sign typecarrier actuated by the sign printing hammer; and a locking bar adjustable by the non-print mechanism into the path of the carrier to prevent sign printing.

29. In a calculating machine, the combination with accumulating mechanism; and regular printing mechanism, including printing hammers; of an auxiliary sign printing device, including a sign printing hammer; an actuator to reset the sign printing hammer; a coupler mechanism to connect the actuator and sign printing hammer to cock the latter; and clearing and subtotal keys to variously adjust the coupler mechanism relatively to the actuator.

30. In a calculating machine, the combination with accumulating mechanism; and regular printing mechanism, including printing hammers; of an auxiliary sign printing device, including a sign printing hammer; an actuator to reset the sign printing hammer; coupler mechanism to connect the actuator and sign printing hammer, to cock the latter; a clearing key to adjust the coupler mechanism relatively to the actuator, for effective operation; and a sub-total key to disable the coupler mechanism relatively to the actuator.

31. In a calculating machine, the combination with accumulating mechanism; and regular printing mechanism, including printing hammers; of an auxiliary sign printing device, including a sign printing hammer; adjustable means to cock the sign printing hammer; and clearing and subtotal keys to variously adjust the cocking means for effective and non-effective operation.

32. In a calculating machine, the combination with accumulating and regular printing mechanisms; of an auxiliary sign printing device, including a sign printing hammer; means to cock the sign printing hammer; normally idle, coupler mechanism adjustable to connect the hammer and hammer-resetting means, a key to adjust the coupler mechanism for effective operation; and another key to adjust the coupler mechanism to ineffective position relatively to the hammer-cocking means.

33. In a calculating machine, the combination with accumulating and regular printing mechanisms, the latter including printing hammers, and hammer-resetting means; of a sign printing device, including a sign printing hammer; normally idle coupler mechanism, adjustable to directly connect the sign printing hammer and the regular hammer-resetting means; detaining means operable independently of the coupler mechanism, to retain the sign printing hammer in cocked position; a key and mechanism operated thereby, to adjust the coupler mechanism for effective operation; locking means to temporarily hold the key where shifted; means to retain the coupler mechanism where adjusted, subsequently to the release of the key, said means adapted to be automatically disabled, to permit the restoration of the coupler mechanism to idle position, after the sign printing hammer-detaining means becomes effective; and means to trip the sign printing hammer-detaining means.

34. In a calculating machine, the combination with accumulating and regular printing mechanisms, the latter including printing hammers, and hammer-resetting means; of a sign printing device, including a normally discharged sign printing hammer; normally idle coupler mechanism adjustable to directly connect the sign printing hammer and the regular hammer-resetting means; a latch operable independently of the coupler mechanism, to retain the sign printing hammer in cocked position; said coupler mechanism adapted to restore to idle position after the latch becomes effective; and means operable preliminary to the registration of an amount on the accumulating mechanism to disable the latch and free the sign printing hammer for operation.

35. In a calculating machine, the combination with accumulating mechanism; and regular printing mechanism, including printing hammers; of an auxiliary sign printing device, including a sign printing hammer; an actuator to cock the sign printing hammer; an adjustable coupler mechanism having an angular slot, the actuator normally idly traversing one arm of the slot; and means to adjust the coupler mechanism to cause another arm of the slot to embrace the actuator.

36. In a calculating machine, the combination with accumulating mechanism; and regular printing mechanism; of an auxiliary sign printing device, including a sign printing hammer; an actuator to reset the hammer; coupler mechanism between the actuator and hammer, having an angular slot; the actuator normally idly traversing one arm of the slot; means to adjust the coupler mechanism to cause another arm of the slot to embrace the actuator; and means to hold the coupler mechanism where adjusted.

37. In a calculating machine, the combination with accumulating mechanism; and regular printing mechanism; of an auxiliary sign printing device, including a sign printing hammer; an actuator to reset the hammer; coupler mechanism between the actuator and hammer, having an angular slot, the actuator normally idly traversing one arm of the slot; means to adjust the coupler mechanism to cause another arm of the slot to embrace the actuator; means to hold the coupler mechanism where adjusted; and a sub-total key to displace the coupler mechanism relatively to the actuator.
38. In a calculating machine, the combination with a keyboard; and accumulating, and regular printing mechanisms, including printing hammers; of an auxiliary sign printing device, including a sign printing hammer; means to cock the sign printing hammer; a latch to retain the sign printing hammer in cocked position; means to trip the latch; and locking means operable independently of the regular printing hammers and controlled by the keyboard, said locking means being displaceable preliminary to the registration of the first amount on the accumulating mechanism, to prevent the release of the latch during idle strokes intervening between the clearing of the accumulating mechanism, and the introduction of the first amount into the machine.
39. In a calculating machine, the combination with a main drive shaft; and accumulating, clearing, and regular printing mechanisms, the last including printing hammers, latches therefor, and hammer resetting means; of an auxiliary, sign printing mechanism; including a sign printing hammer; coupling means controlled by the clearing mechanism, to enable the hammer resetting means to cock the sign printing hammer; detaining means individual to the sign printing hammer, to retain the latter cocked; and means to release the detaining means, independently of the regular printing mechanism, as an incident to the entry of the first item into the machine, after a clearing operation.
40. In a calculating machine, the combination with a main drive shaft; and accumulating, clearing, and regular printing mechanisms, the last including printing hammers, latches therefor, and hammer resetting means; of an auxiliary, sign printing mechanism; including a sign printing hammer; coupling means controlled by the clearing mechanism, to enable the hammer resetting means to cock the sign printing hammer; detaining means individual to the sign printing hammer, to retain the latter cocked; a displaceable lock to prevent tripping of the detaining means during idle

strokes intervening between a clearing operation and the entry of the first item of a new list into the machine; and flexible means actuated at each operation of the main drive shaft, to trip the detaining means after the displacement of the lock.

41. In a calculating machine, the combination with a main drive shaft; and accumulating and regular printing mechanisms; the latter including printing hammers, and hammer-resetting means; of a sign printing hammer settable by the regular resetting means; a detainer to hold the sign printing hammer cocked; yielding means tensioned at each operation of the main drive shaft, to trip the detainer; a displaceable lock normally in the path of a part of the yielding trip means to arrest the latter and thereby prevent the tripping of the detainer; and means to displace the lock.

42. In a calculating machine, the combination with a main drive shaft; and accumulating, clearing and regular printing mechanisms, the last including printing hammers, latches therefor, and hammer resetting means; of an auxiliary, sign printing mechanism, including a normally discharged sign printing hammer; normally idle coupling means controlled by the clearing mechanism; to enable the hammer resetting means to cock the sign printing hammer; detaining means to retain the sign printing hammer cocked; disconnecting means engaged by the coupling means during the cocking of the hammer to release the coupling means from the hammer resetting means; yieldable means actuated at each operation of the main drive shaft, to trip the detaining means; and a lock displaceable independently of the regular printing mechanism to prevent the tripping of the detaining means.

43. In a calculating machine, the combination with a main drive shaft; and accumulating, clearing and regular printing mechanisms, the last including printing hammers, latches therefor, and hammer resetting means; of an auxiliary, sign printing mechanism, including a normally discharged sign printing hammer; normally idle coupling means controlled by the clearing mechanism, to enable the hammer resetting means to cock the sign printing hammer; detaining means to retain the sign printing hammer cocked; disconnecting means engaged by the coupling means during the cocking of the hammer to release the coupling means from the haminer resetting means; means to trip the detaining means; and a lock displaceable independently of the regular printing hammers, to prevent the tripping of the detaining means.

ARTHUR PENTECOST.
